6 Claims. (Cl. 260—412.8)

1

This invention relates to improvements in processes and apparatus for continuous percolation-extraction with solvent, and particularly to processes and apparatus for the continuous percolation-extraction by solvent of oil from oil-bearing materials.

This invention constitutes an improvement on the processes and apparatus shown and described in U. S. Letters Patent No. 2,273,557 issued to applicant on February 17, 1942.

In carrying out solvent extraction of vegetable seeds according to the process shown and described in my said U. S. Patent No. 2,273,557, difficulties in relation to solvent vapors have been encountered when hot solvent or solvent near its boiling point is used. This is especially true when using an extractor with a feeding hopper through which the process material is continuously fed by gravity to a horizontal moving conveyor, the bottom of which comprises a wire screen. In Fig. 3 of said patent a moving column of material to be extracted, such as vegetable seeds in flaked form, is moved by gravity and fed through a feeding hopper to a horizontal rectangular trough on the conveyor belt. The trough is open at its top within an outer vapor-tight casing, and moves with the material beneath spraying sections in which a solvent, such as liquid paraffine hydrocarbons or any other solvent in which the process material sinks, is sprayed on top of the horizontal column of material, percolates through it and collects in a container-section located below the corresponding spraying section, the solvent being then withdrawn and passed on to the next spraying section in countercurrent with the moving bed or horizontal column of material under process. In this type of apparatus, when the flakes are fed continuously to a moving wire-screen apron-conveyor through a gravity-feeding hopper, the solvent vapors have a tendency to pass through the flakes and into this hopper, and from the hopper to the atmosphere, thus causing loss of solvent and creating a dangerous explosive condition. While there are airlocks on the market to remedy a condition of this character, they are not dependable; have a tendency to pulverize flaked material and are subject to freezing.

One of the objects of this invention is to avoid the difficulties above mentioned by employing in an extractor having a belt type conveyor (through which solvent but not the process material is permitted to pass) and which is movable through a vapor-tight casing, a gravity-feeding

2

hopper and providing in said hopper a liquid seal so that any solvent vapors (which are released from the solvent and developed in the vapor-tight casing during extraction) are kept from seeping to the atmosphere through dry material or dry flakes which are being continuously fed through such gravity-feeding hopper.

I have observed that when solvent-spraying nozzles are used to flood with solvent a bed or column of flakes in the several sections or stages of the moving column of material, a relatively high amount of electric power is required for pumping to effect proper spraying by keeping adequate pressure at the nozzles. Furthermore, the use of spraying nozzles has a tendency to fail in evenly flooding the bed of material, so that channeling of the solvent liquid occurs and effective extraction is impaired. Also the nozzles become clogged with fines that may occur in the miscella.

Another object of my invention is therefore in an apparatus of the type specified to introduce into percolating sections (which are alternately located in relation to draining and/or diffusion sections) solvent material through a perforated surface in a solvent-container filled or partially filled with solvent, said perforated surface being disposed over or above the top portion of the horizontally movable column or bed of flakes and thus to provide an even rain like supply of solvent or miscella to cover and be evenly applied and sharply defined to given areas along the whole upper surface of the moving column of flakes as it passes under such perforated surfaces.

I have also observed that in prior art devices the rate of percolation through a bed of a given depth of flakes at the material-feeding end of the extractor (which is remote from the fresh solvent feed in a counter-current apparatus) is relatively slow as compared to the same depth of the bed further on along the extractor. This is due to the relatively high viscosity of the miscella at this point and to the counter-current action. Such rate of percolation is not only reduced by the relatively high concentration of miscella which accounts for the high viscosity, but also by the relatively low temperature of the flakes fed to the extractor which constitute the bed of material. In fact, at the feed end of the extractor the miscella is not only gradually enriched in oil by its countercurrent progress through the apparatus, but also is further enriched in this feeding section by free oil dissolved

during percolation through the fresh flakes introduced into the extractor at this point.

Another object of my invention is therefore in an apparatus of the type specified to wash in parallel current in the feeding hopper from the column of flakes the oleaginous seed oil which is freed during the flaking or grinding operation and such wash is, in accordance with the preferred form of my invention, accomplished by providing, preferably at the material-feeding inlet or hopper of the extractor, means for building up a hydrostatic head of solvent material so that a greater quantity of such solvent material or miscella per unit of time may be recycled through the same bed than would be possible by simply flooding the bed in question. Such a hydrostatic head enables the increasing of the depth of the bed of flakes at the loading end, and fine particles sifted through the screen during the loading operation of the conveyor may be more effectively filtered through the bed when recycled with miscella in such percolating-feeding section.

I have also found that in feeding material to a moving screen, perforated conveyor or the like through a hopper located directly above such conveyor, the flow of material through the hopper is not even throughout the area of discharge and above the same because the material has a tendency to fill, in the first place, the fore part of the conveyor which enters the filling area in an empty state. Consequently, to obtain an even flow of material through the feeding hopper such hopper would have to have a very narrow elongated shape, which is impractical due to arching of the material. Furthermore the percolating area is greatly reduced with the result that less G. P. M. are circulated or recycled. Furthermore, I have found that a great amount of fine solid particles contained in the flaked material falls or is sifted through the conveyor or wire screen during the feeding stage; that these fine particles collect in the receiver beneath the screen with the percolating miscella, and that the amount of such fine particles is in proportion to the bare area of the screen on which the flakes are fed.

Another object of my invention is, therefore, in a device of the character specified to provide means to cause material such as flaked oil-bearing seeds to flow evenly through a feeding hopper of relatively large area and to be fed or fall directly on the wire screen or perforated belt, and in the preferred embodiment of my invention, the material being fed is stratified during the feeding operation. This stratifying is accomplished by dividing the longitudinal area of my feeding hopper into a plurality of sections or compartments by the use of properly located and dimensioned baffles adapted to guide the material being deposited on the belt or screen into a plurality of series of successive layers, each positioned in a higher plane above the belt or screen and starting from the line or point where the empty screen or belt enters the bottom or open area of the feeding hopper. With such an arrangement of baffles only a relatively small part of the material being fed through the hopper falls on the bare screen, consequently minimizing the amount of fines that may fall or sift through the screen, and also with this arrangement of baffles the flow of material from and through the hopper is even and constant throughout the area of movement therethrough.

Another object of my invention is, in an apparatus of the type specified, to provide an over-

flow from each of the perforated surfaces hereinabove referred to and to direct such overflows to receiving containers below the spraying or deluging areas where percolated miscella is collected, such overflowed and percolated miscella being then recirculated through perforated surfaces at a constant rate by recycling pumps so that the delivery end of such pumps is not subjected to any pressure other than the liquid head contained in the discharge conduit and the perforated surfaces are without restriction of orifices (as is the case when spray nozzles are used), thus reducing the power required for the pumps and eliminating the clogging which occurs when nozzles are employed.

Another object of my invention is in a device of the character specified to provide in the feeding hopper above a given depth of material being fed to the extractor a hydrostatic liquid head preferably by recycling a relatively large quantity of miscella from a liquid receiving container below the feeding hopper to a compartment above or on top of the bed of flakes in the feeding hopper and to keep this hydrostatic liquid head constant by regulating the amount of miscella in circulation, so that a constant overflow will occur from the feeding hopper back to the receiving container from which the percolated miscella is being recycled.

With these and other objects in view the invention comprises the combination of steps and members so combined as to coact and cooperate with each other in the performance of the functions and the accomplishment of the result herein contemplated, and the apparatus comprises in one of its adaptations the species or preferred form illustrated in the accompanying drawing in which:

Fig. 1 is a longitudinal section through a continuous filtering extraction apparatus embodying my invention;

Fig. 2 is a fragmentary view in horizontal section on the line 2-2 of Fig. 1, looking in the direction of the arrows and showing the front portion of the apparatus illustrated in Fig. 1; and

Fig. 3 is a vertical section on the line 3-3 of Fig. 1, looking in the direction of the arrows.

Referring now to these drawings which illustrate a preferred embodiment of my invention, 1 indicates a vapor-tight tunnel casing which may be supported in any suitable manner (not shown). Within said casing 1 provide a continuously-moving conveyor 2 which is preferably of the endless apron type having a wire screen surface 2^a connected with a pair of sprocket-chains 2^b, each composed as shown in Fig. 3 of pairs of chain link-bars 2^c arranged on opposite sides of the screen surface 2^a, said chain link-bars 2^c extending around and being driven by sprockets 2^d. Each chain includes flanged chain rollers 2^e mounted on and connected with conveyor supporting rods 2^f, said rollers 2^e being independently supported on and running along tracks 2^g mounted on shelves 2^h connected with the inner surface of the casing 1. The wire screen 2^a is thus stretched between said chain 2^b and longitudinally disposed trough-forming stationary baffles 4 are positioned to extend along the side edges of the screen 2^a to produce an extraction trough 5 adapted to receive a horizontal column of process material 6, which when such material is flaked is a "fake bed."

In the preferred embodiment of my invention, the material under process comprises flaked oil bearing seeds. Handling of such flakes at the

feeding point is a very delicate operation because any mechanical means employed will have a tendency to break the flakes, thus producing fines, and in the embodiment illustrated, the flaked material enters the extraction trough 5 of the extractor from a surge hopper 8^a passing through a star feeder 8 at a proper and suitable rate to a feeding bed A within feeding hopper 7, the lower end of which is securely connected by a vapor-tight joint with the vapor-tight casing 1, and a baffle casing 9 positioned intermediately and connected with the star feeder 8 and the feeding hopper 7 conveys the flakes below the liquid level 7^b of a combined hydrostatic head and liquid seal 25, which, as hereinafter specified, is provided in said hopper 7. From the surge hopper 8^a the flakes are passed by gravity to feeding-bed A in the feeding hopper 7, and in this feeding hopper 7 such feeding bed of flakes is divided into a plurality of sectional feeding columns and deposited by gravity in stratified layers on the moving upper run of wire-screen surface 2^a. In order to cause such flakes to be so divided and deposited in stratified layers on said moving screen surface, I provide within said feeding hopper 7 a plurality of vertically-disposed material-distributing baffles 10, which extend transversely within said feeding hopper 7 directly across and above the surface of said wire screen and produce a plurality or series of feeding sections 11, 11^a, 11^b and 11^c. In accordance with the preferred form of my invention illustrated, the lower edges of these baffles 10, which form the top edges of a plurality of sectional feeding outlets 12, are, beginning with the baffle closest to the front of the hopper 7, arranged at successively increasing heights above the wire screen and form a sectional bed of flakes comprising a plurality of stratified evenly distributed layers of suitable depth, which bed is then conveyed by the conveyor screen through the vapor-tight tunnel casing 1 to the discharge outlet 13 thereof.

As shown, the front or feeding end of the endless screen conveyor 2 is mounted within a front compartment 1^b and extends to a position which is forward of the feeding hopper 7, and when this conveyor is started the conveying screen surface 2^a enters the bottom portion of the feeding hopper 7 in an empty or bare state at what I shall call the sifting area 7^a. Immediately upon entry of the screen surface, a layer of flakes will be deposited by gravity through the first of the feeding openings 11, 11^a, 11^b, 11^c on the bare screen section at this sifting area. With this arrangement of baffles, therefore, only a relatively small part of the material being fed through the feeding hopper 7 falls on the bare screen and consequently the amount of fines that may fall or sift through the screen is minimized. Also the process material or flakes will be kept in their proper place in the hopper by the baffles 10 and the depth of the first layer will be equal to the clearance space between the lower edge of the first baffle 10 and the wire screen conveyor 2. Further movement of the screen area on which the first layer of flakes is then mounted will, when the screen travels below the next space between two of the baffles 10, cause the formation of a second layer of flakes. However, after passing the first baffle 10 the screen will not be bare but will be covered by a layer of flakes that was formed in the first section 11. This first layer of flakes will thereafter prevent fines which are mixed with the flakes in the succeeding layers from passing through the screen conveyor. Success-

sive layers will thus be laid from the sections 11^a, 11^b and 11^c, passing through the sectional feeding outlets 12 below the lower edges of the baffles. The clearance space between the lower edge of the first baffle and the conveyor will determine the thickness of the first layer deposited on the moving screen and the clearance spaces between the several edges of the second and succeeding baffles will determine the thickness of the stratified layers which constitute the bed of flakes. Baffle 10^a, which as shown comprises an extension portion of the baffle casing 9 and the length of which may be suitably regulated, will determine the final depth of the bed of flakes 6 that will be carried on the screen conveyor throughout the length of the extractor casing.

To keep the bed of flakes A at the desired depth in the feeding hopper 7, the star feeder 8 may be revolved at the desired R. P. M. so that the quantity of flakes fed will correspond to the quantity of the extracted material discharged from the extractor casing at the discharge outlet 13.

Along the upper surface or top of said vapor-tight tunnel casing 1 and above the bed of flakes 6 so formed on the wire screen I provide a plurality or series of spraying boxes 14—14^a, 14^b, 14^c, 14^d which pass liquid solvent onto the bed of flakes within the trough 5. Such liquid solvent will then percolate through such bed of flakes, and I provide below the conveyor 2 in a position so as to receive liquid which so percolates through said bed of flakes riding on the wire screen 2^a a series of receiving containers or stage receivers 15^a, 15^b, 15^c, 15^d and 15^e. Into one, 14^d, of these spraying boxes, fresh solvent is fed through conduit 16 and regulated by valve 18^a. It is desirable in an apparatus of the type specified to provide means in the body of the casing 1 for causing a flow of the solvent liquid or miscella in counter-current to the conveying movement of the process material, and into all of these boxes 14—14^d solvent liquid or miscella is finally fed in such counter-current as hereinafter more particularly specified.

In order to percolate liquid from the boxes 14—14^d through the bed of flakes, as aforesaid, I preferably provide in said series of boxes 14—14^d perforated surfaces 20, and, in the preferred form of my invention illustrated, the bottoms of the spraying boxes are perforated so that the required quantity of solvent or miscella will pass through these perforations and will provide an even rain like supply of solvent or miscella to cover and be evenly applied and sharply defined to given areas along the whole upper surface of the moving column of flakes as it passes under such perforated surfaces.

In the apparatus illustrated, I provide an overflow from the perforated surfaces 20 and boxes 14—14^d hereinabove referred to and I direct such overflows into the receiving containers 15—15^e below the spraying or deluging areas where percolated miscella is received and collected. As shown, such overflow is accomplished by the conduits 19 and the overflowed solvent material or miscella mixed with the percolated miscella also received in such receiving containers is then supplied to the boxes 14—14^d and recirculated through the perforated surfaces at a constant rate by recycling pumps 17—17^d in such manner that the delivery ends of such pumps are not subjected to any pressure other than the liquid head in the connected conduits and as the perforated surfaces are without restriction of orifices,

as is the case when spray nozzles are used, the power required for the pumps is reduced. Also the clogging of the orifices with fines that occur in the miscella is substantially avoided and reduced over prior art nozzle devices.

The overflow from each of the spraying boxes 14-14^d directly through conduits 19-19^d back to the receiving containers or stage receivers 15-15^d causes the liquid supply or body in such spraying boxes 14-14^d to be kept constant and the level 16^b thereof to be maintained, and this maintenance of liquid level in the spray boxes will cause a uniform rain even if the spray boxes are not supported in truly horizontal positions.

The quantity of percolated liquid comprising miscella supplied as aforesaid by the pumps 17-17^d to the spraying boxes 14-14^d and thus recirculated through the spraying boxes is preferably adjusted when necessary by blinding a portion of the perforations according to requirements rather than by throttling the discharge of the stage pumps 17-17^d.

In the embodiment of my invention illustrated, a series of solvent heaters 24-24^c are applied to conduits which conduct fresh solvent and miscella in steps of the counter-current movement thereof, and, as shown, such heaters 25 are applied to the fresh solvent conduit 16 and the pump-delivery conduits 21, 21^a and 21^b. Obviously the fresh solvent in conduit 16 and miscella in conduits 21, 21^a and 21^b being supplied to the boxes 14-14^d may be heated to any desired temperature by the heaters 24-24^c and solvent vapors 26 above the bed 6 of flakes will be produced.

To start the percolation-extraction operation in the casing body 1, the feeding hopper 7 is first filled with process material or flakes. Then the conveyor screen 2^a is started at a proper speed until the bed of flakes in the extractor casing reaches a point below the spraying box 14^d adjacent to the discharge outlet. Movement of the conveyor is then stopped. Fresh solvent of the desired temperature is then fed continuously at a proper rate into said spraying box 14^d and the solvent percolated from this box 14^d is collected in the stage receiver 15^e and is then recirculated by the pump 17 to said box 14^d. When the stage receiver 15^e is full, percolated solvent which will contain some oil in solution and may properly be called "miscella" will overflow through conduit 18 from said stage receiver 15^e to the next adjacent stage receiver 15^d. When the necessary quantity of liquid is collected in the stage receiver 15^d the pump 17^a is started and the miscella is pumped to the box 14^c. From the box 14^c the miscella will drop through the perforations in the bottom thereof to the upper surface or top of the bed of flakes and after percolation therethrough will be collected in the stage receiver 15^d and will from that stage receiver be recycled through the pump 17^a to the box 14^c. When the stage receiver 15^d is full, the miscella will overflow and pass by conduit 18^a to the stage receiver 15^e and from there through the pump 17^b will be recirculated to the spraying box 14^b from which it will percolate through the bed of flakes back through the stage receiver 15^e and when this stage receiver 15^e is full, the miscella will overflow and pass by conduit 18^b into the stage receiver 15^b and so on, the pumps after starting being kept going.

I have found that it is desirable and important that divisions or gaps be located between the several spraying boxes through which the solvent

and miscella are percolated to provide what in my above-mentioned patent I have called "diffusion zones," as they provide also a means for partial or total draining (according to the length of such divisions or gaps) of the miscella from the bed of flakes before the material during its travel in counter-current toward the outlet of the apparatus reaches the next zone of percolation or flooding through which the miscella of less concentration is sprayed.

It will be noted that in Fig. 1 the miscella draining through the diffusion or draining sections falls into the stage receiver which is positioned below the corresponding spray box and that these stage receivers are designed or so arranged and extended as to collect miscella from the spraying box or section directly above it and from an adjacent draining section. For example, the stage receiver 15^e will collect miscella percolating through the box 14^d and part of the miscella draining from the diffusion or draining section 1^c.

The stage receivers will fill successively and will overflow because fresh solvent entering the box 14^d is continuously fed at a given rate and, as aforesaid, moves through the body of the casing 1 in counter-current to the movement of the process material. During this travel, the solvent picks up oil to form a miscella which gradually increases in oil concentration so that when miscella reaches an area below the first spray box 14^d, I preferably provide means, such as conduit 18^c, whereby the miscella by-passes said stage receiver 15^e and flows to the stage receiver 15 beneath the hopper 7.

By the pump 17^e solvent material or miscella is fed from the stage receiver 15 to a compartment 22 in the top portion of the feeding hopper 7 in which the flake bed A is provided and forms therein the combined hydrostatic head and liquid seal 25. This bed of flakes A is kept constant as far as possible and the depth thereof will depend upon the physical characteristics of the material under process which will preferably be prepared so as to present a known resistance or friction to the flow of solvent through the bed.

The rate of percolation through the bed of flakes A on the screen 2^a, which as aforesaid is of predetermined depth, will be regulated so as to always keep the hydrostatic head 25 of miscella above or on top of the bed of flakes A. This hydrostatic head 25 will partially fill the feeding hopper 7 and will act as a liquid seal so that the solvent vapors 26 which are released from the solvent and contained in the vapor-tight enclosing casing 1 in which the conveyor operates will be kept from seeping to the atmosphere through dry material or dry flakes, which would conventionally be continuously fed through such feeding end of the hopper if such material were not kept immersed in liquid. This arrangement will enable the heating at the final stages of extraction of the solvent and the miscella to a point near the boiling point thereof, thus greatly facilitating the extraction operation.

It will be understood, that preferably only the fresh solvent or weak miscella is heated to facilitate the complete extraction and diffusion (in the stages near the discharge end), and the temperature of the solvent is gradually decreasing (from the inlet to the outlet) due to the presence of cold flakes at the inlet. The pure solvent also loses temperature in supplying heat to the bed of flakes while they travel toward the exit or outlet. The temperature of the miscella used by me as a seal, therefore, is near to the temperature of

the material or flakes when they enter the hopper. As shown, I provide a heater 24 on the fresh solvent conduit 16 and also apply heaters 24^a, 24^b and 24^c on the recycling conduits 21, 21^a and 21^c from the pumps 17, 17^a and 17^b.

An overflow 23 will be located so as to keep the hydrostatic head 25 at a desired level 7^b and the solvent material or miscella therein will move through the process material in the hopper in parallel current with the feeding movement of said material.

This hydrostatic head will assist also in overcoming the friction encountered by the miscella during percolation through the bed of flakes A, which in the feeding hopper is deeper than on the apron conveyor. Said hydrostatic head will also overcome resistance to percolation due to the high viscosity of miscella at the forward or feeding end of the extractor. Also, during the recycling in the feeding hopper the free oil liberated from the seeds during the flaking operation will be completely washed out of the flakes and a high concentration of miscella will be procured.

When a solvent of higher specific gravity than the material under process is used, as for example trichloroethylene, a hydrostatic head may be provided even in this case if a relatively high concentration of the miscella used for the hydrostatic head is employed in which the material will sink.

In accordance with the preferred form of my invention, when the stage receiver 15 beneath the feeding hopper 7 is filled, the miscella therein will overflow in the reverse direction. This reverse flow is desirable because when the extractor operates continuously a certain amount of fine particles will sift through the wire screen during the loading of the screen conveyor and these fine particles are only partially filtered during the recycling of the miscella through the feeding hopper 7. Such fines are thus collected beneath the hopper in said stage receiver 15 and when the stage receiver 15 overflows reversely to the stage receiver 15^a will be recycled with the miscella by the pump 17^a through the spray box 14^a to the top or upper surface of the moving bed of flakes on the screen conveyor.

After the operation of loading the flakes from the hopper no more fines will be sifted through the screen because the bed of flakes will not be further disturbed after such flakes leave said feeding section.

In the preferred form of my invention, when the stage receiver 15^a is filled, miscella subsequently added from an overflow conduit 19 and from the receiver 15 will leave said stage receiver 15^a and the extractor through overflow conduit 27 and from this conduit such miscella will pass to distillation means for the separation of the oil from the solvent.

The above described operation which is desirable to prime the extractor will continue for a length of time depending upon the characteristics of the material under process, and preferably a sample of the material taken from the bed of flakes under the spraying box 14^a adjacent to the discharge opening 13 will be procured and examined or analyzed to show the extent of the extraction that has been reached.

After the aforesaid priming, the conveyor is then started at a proper speed to provide the necessary time required for extraction. Such time is normally from six to twelve inches per minute. When the extractor is in equilibrium, the traveling bed of flakes is thus submitted to counter-current extraction because the flakes on

the conveyor pass under the deluging areas through which miscella of increasing concentration percolates; the richer miscella thus percolating through the section nearer the feeding end and the leaner miscella percolating through the section nearer the discharge outlet. The fresh solvent thus percolates through the spent flakes at the discharge end.

The length of the apparatus may be considerably shortened and the time of extraction correspondingly reduced by subjecting the extracted flakes leaving the apparatus to a squeezing action in squeezing devices such as shown and described in Patents Nos. 2,184,248 and 2,203,666 issued to 10 applicant, and through which devices the larger part of the solvent held up physically inside the flakes may be liberated in a liquid state by mechanical pressure. Thus, the extracted flakes on their way to the solvent elimination phase of the 15 process will contain much less solvent than if the flakes were subjected only to draining action at the exit of the extractor. Such draining time would of necessity be relatively long and, of course, extra length of the apparatus would have 20 to be provided for such purpose. It will be understood that the less solvent retained by the flakes means less steam used in eliminating the solvent from the extracted flakes during the solvent-elimination step.

In some cases a squeezing action to remove solvent retained might not be desirable, and in such cases it may be desirable to let the solvent drain by gravity from the bed of flakes before it reaches the discharge outlet. In such cases, the length 25 of the rear end 1^a of the conveyor to the rear of the box 14^a may be increased to provide it for such drainage, and in such cases the drained liquid will be collected in the stage receiver extending in the rear stage container, which of 30 course would be extended for this purpose or if desired an additional receiver might be provided.

As shown, the casing 1 at the rear end is provided with a conventional vent 28 which leads vapors from said rear end to a condenser or other suitable outlet therefor, and a similar vent 29 is provided in a process-material conduit 38 which connects with and is positioned between the star 35 feeder 8 and the baffle-casing 9.

As illustrated, the baffle-casing 9 extends into 40 the feeding hopper 7 and the compartment 22 for the hydrostatic head 25 is formed between the outer wall or surface of said baffle-casing 9 and the inner wall or surface of the feed hopper 7.

It will be understood that the vent 29 leads to 45 a condenser such vapors as are formed in the hopper 7 and that pass through the flakes in the baffle casing 9.

Having described my invention, I claim:

1. A process for continuous percolation extraction with solvent in systems of the horizontal screen-conveyor type consisting in feeding downwardly by gravity through a feed hopper a column of oil-bearing process material, guiding said column of process material laterally from said hopper, passing through the hopper and in parallel current with said process material a volatile liquid solvent to wash out from the process material the oil which is freed during operations of preparing such solid materials for extraction and forming in said hopper a liquid seal of said solvent above said process material to keep solvent vapors formed in the process from seeping through the process-material at the inlet thereof.

2. A process for continuous percolation extraction with solvent in systems of the horizontal

screen-conveyor type, the steps of passing solid oil-bearing process material downwardly by gravity through a feed hopper, guiding such oil-bearing process material laterally from said hopper, forming above said solid oil-bearing process material being fed a hydrostatic head of volatile liquid solvent material, passing such volatile liquid solvent material under pressure of said hydrostatic head through said process material being fed in parallel current to the gravity movement thereof, whereby a greater quantity of such solvent liquid per unit of time may be passed through said bed than would be possible by simply flooding the bed.

3. A process for continuous percolation extraction with solvent in systems of the horizontal screen-conveyor type, the steps of passing solid oil-bearing process material downwardly by gravity through a feed hopper, guiding such process material laterally from said hopper, forming above said solid process material being fed a hydrostatic head of volatile liquid solvent material, passing such volatile liquid solvent material under pressure of said hydrostatic head through bed of said solid oil-bearing process material being fed in parallel current to the gravity movement thereof, whereby a greater quantity of solvent liquid per unit of time may be passed through said bed than would be possible by simply flooding the bed, receiving and aggregating below said body of solid oil-bearing process material the volatile liquid solvent so fed from the hydrostatic head and recycling such aggregated solvent to said hydrostatic head.

4. A process for continuous percolation extraction with solvent in systems of the horizontal screen-conveyor type, the steps of passing solid oil-bearing process material downwardly by gravity through a feed hopper, guiding such process material laterally from said hopper, forming above said solid process material being fed a hydrostatic head of volatile liquid solvent material, passing such volatile liquid solvent material under pressure of said hydrostatic head through a bed of said solid oil-bearing process material being fed in parallel current to the gravity movement thereof, whereby a greater quantity of solvent liquid per unit of time may be passed through said bed than would be possible by simply flooding the bed, receiving and aggregating below said body of solid oil-bearing process material the volatile liquid solvent so fed

5 from the hydrostatic head and recycling such aggregated solvent to said hydrostatic head and maintaining said hydrostatic head of material at a given level by causing an overflow of solvent material above said level.

5. In a process for continuous percolation extraction with a volatile solvent in systems of the horizontal screen-conveyor type, the steps of feeding a body of solid oil-bearing process material by gravity to a conveyor, dividing the body of oil-bearing process material being fed into a plurality of successive transversely registering columns of varying heights, one behind the other, and conveying such columns of said oil-bearing process material in a direction toward a discharge opening through feed openings arranged in planes one above the other to produce a bed of stratified layers of such oil-bearing process material in varying positions one above the other.

10 6. In a process for continuous percolation extraction with a volatile solvent in systems of the horizontal screen-conveyor type, the steps of feeding solid oil-bearing process material by gravity through a hopper to provide a body of such oil-bearing process material for conveyance, dividing said solid oil-bearing process material into a plurality of successive transversely registering columns, feeding for conveyance by said conveyor a relatively narrow layer of said oil-bearing process material from the first of said successive columns to minimize the bare surfaces of the screen conveyor and reduce the quantity of fines passing therethrough during the feeding of such process material to said conveyors and simultaneously feeding process material from another column above said first layer.
